UNITED STATES PATENT OFFICE.

FREDERICK J. CLARK, OF BUFFALO, NEW YORK, ASSIGNOR TO EASTMAN MACHINE COMPANY, OF BUFFALO, NEW YORK.

CLOTH-CUTTING MACHINE.

No. 910,172.

Specification of Letters Patent.

Patented Jan. 19, 1909.

Application filed September 6, 1907. Serial No. 391,589.

To all whom it may concern:

Be it known that I, FREDERICK J. CLARK, a citizen of the United States, residing at Buffalo, in the county of Erie and State of New York, have invented a new and useful Improvement in Cloth-Cutting Machines, of which the following is a specification.

This invention relates more particularly to portable cloth cutting machines having reciprocating motor-operated knives for cutting the cloth.

One of the objects of the invention is to so construct a machine of this character that the motor shaft will be arranged lengthwise of the machine and the cross head for the knife will be below and in the vertical plane of the motor shaft and connected therewith and will be arranged fore and aft of the machine in guide ways, one in front of the other, thereby giving an unobstructive view of the cloth in front of the knife to the operator of the machine and greatly simplifying the construction and producing a more evenly balanced and better appearing machine.

Heretofore it has been customary in machines of this character, to arrange the cross head and its guide ways crosswise of the machine as distinguished from lengthwise. In such construction, when the motor shaft is arranged lengthwise of the machine, the cross head and its guide ways with their supports materially increase the width of the front of the machine directly above the knife and interfere with the operator's view of the pattern on the cloth he is cutting. To overcome this, machines have been constructed with the motor shaft arranged crosswise of the machine and extending to one side of the standard, but this construction produces a one-sided and unevenly balanced machine. In a machine according to the present invention, the lengthwise arrangement of the motor shaft is retained and the cross head and guide ways for the knife are also arranged lengthwise of the machine and are located above the knife and somewhat to one side of the standard.

Other objects of the invention are to provide adjusting means for the guide ways of the cross head, which can be readily operated, whereby the cross head can be secured in place between them and the guide ways adjusted to take up any wear of the parts without changing the position of the cross head;

to provide a yielding bearing for the supporting rollers of the machine so constructed that the rollers can be readily removed for cleaning; to pivotally secure the cloth-lifting heel and toe plates to the base of the machine in such a manner that they can be easily disconnected therefrom; to provide a flexible support for the lamp of the machine to lessen the vibration thereof when the machine is being operated; and to generally simplify and improve the construction and operation of cloth-cutting machines in the manner hereinafter more specifically described and claimed.

In the accompanying drawings: Figure 1 is a side elevation, partly in section, of a cloth cutting machine embodying the invention. Fig. 2 is a bottom plan view of the base thereof. Fig. 3 is a perspective view of one of the bearing plates for the supporting rollers. Fig. 4 is a top plan view of the lamp and its support. Fig. 5 is a sectional elevation, on an enlarged scale, of portions of the base and one of the cloth-lifting plates. Fig. 6 is a front sectional elevation of the machine on line 6—6, Fig. 1. Fig. 7 is a sectional plan view thereof, on line 7—7, Fig. 1. Fig. 8 is a side elevation, on an enlarged scale, of the adjusting means for the guide ways for the cross head. Fig. 9 is a cross section of the same, on an enlarged scale, on line 9—9, Fig. 8. Fig. 10 is a cross section of the same on line 10—10, Fig. 8.

Like letters of reference refer to like parts in the several figures.

A represents the foot or base of a cloth cutting machine, B the standard, C the motor-supporting frame carried by the standard, D the motor, and E the reciprocating knife driven by the motor and adapted to reciprocate in a guide slot in the standard. The motor D has a shaft *d* journaled in the frame C lengthwise of the machine, and provided at its forward end with a suitable crank or crank head F connected by a rod or pitman *f* with the knife cross-head. A suitable casing *f'* incloses the crank head F and the upper portion of the pitman *f*, having a rearwardly opening slot at its bottom through which the pitman passes. This casing is removably secured to the frame C by oppositely extending hooks or slotted lugs *f''* at the top and bottom thereof which engage headed screws *f''* secured in the frame C. By loosening the screws *f''* and partially

turning the casing f' it will be released, when it can be pulled forwardly off of the machine. The casing f' protects the inclosed parts from dirt and also protects the operator from injury.

G represents the cross head for the knife. This cross head is preferably provided with front and rear vertical V-shaped edges which engage and reciprocate in correspondingly shaped ways in guide blocks H and H' arranged one in front of the other lengthwise of the machine. The frame C has a forward extension J above and at one side of the standard B, and the guide blocks are secured to one side of this extension by screws j which pass through horizontal slots j' in the extension.

Suitable means are provided for adjusting the guide blocks H and H' toward and from the knife cross-head. In the construction shown (see Figs. 8, 9 and 10), the guide blocks are provided on the sides thereof adjacent to the frame extension J with lugs h h' at their upper and lower ends which extend through horizontal slots in this extension. The upper and lower pairs of lugs are connected by adjusting screws K having right and left screw threads on opposite ends thereof engaging in correspondingly threaded openings in the ends of the lugs h of the rear guide block H and internally threaded nuts h^2 secured in the lugs h' of the front guide block H'. The adjusting screws K have enlargements suitably fashioned for the engagement of a tool or wrench, and these enlargements engage in vertical slots h^3 in the frame extension J for holding the screws from endwise movement when turned. By turning the adjusting screw one way or the other the guide blocks can be adjusted toward or from the cross head as required.

In order to permit a separate independent adjustment of the guide blocks for the purpose of securing the cross-head in its proper position between them, the lugs h' of the front guide block are split at their ends and the nuts h^2 are clamped between the split portions of the lugs by clamping screws h^4 . When the nuts are clamped and held from turning in the lugs, any rotation of the adjusting screws produces a corresponding movement of both guide blocks.

When the clamping screws h^4 are released the split ends of the lugs separate sufficiently to allow the nuts h^2 to turn with the adjusting screws and thus prevent movement of the forward guide block. This allows the adjusting screws to be turned to separately adjust the rear guide block without causing any movement of the front guide block. The nuts h^2 are provided with suitable heads h^5 , Figs. 8 and 9, by which they can be turned on the adjusting screws K and which are adapted to engage the sides of the split lugs h' . When the rear guide block has been ad-

justed to engage the cross head, the nuts h^2 are screwed up on the adjusting screws K to move the front guide block into engagement with the cross-head. This enables the cross head to be located in its proper position above the knife and the guide blocks adjusted to engage the cross head and hold the same in such position.

After the guide blocks have been adjusted into proper engagement with the cross head, the screws j are tightened to hold the same firmly in position upon the frame extension J. In operating the machine, the operator generally guides the machine with his right hand and therefore stands on the left side of the machine. The frame extension is accordingly located so that it extends in front of the machine at the right of the standard in order that the extension and the adjusting means for the guide blocks carried thereby are on the side of the machine opposite to the operator and thus do not obstruct his view of the knife and the cloth in front of the same.

L represents the usual presser foot secured to the front of the frame extension and l the usual finger screw for adjusting the same. The base of the machine is of ordinary form except as hereinafter described, comprising the main base plate A having beveled side edges, and spring-pressed cloth-lifting heel and toe plates M M' hinged to the main plate. These cloth-lifting plates, on their underside, are provided with suitable lugs m having adjacent to the base A open-bottomed slots m' therein adapted to receive hinge pins m^2 connecting suitable pairs of hinge ears m^3 formed integral with the base A at each end thereof. Suitable screws m^4 are countersunk into the hinge lugs m and their heads serve to hold the hinge pins m^2 in the slots in the hinge lugs m and at the same time allow the heel and toe plates to swing on the hinges thus formed. By releasing the screws m^4 the heel and toe plates M M' may be readily disconnected from the base plate A. As usual, springs n n' are provided for pressing the toe and heel plates down on the support upon which the machine rests.

The base is provided with supporting rollers O, which, as usual, are capable of yielding to absorb the vibrations produced by the reciprocating knife so that the machine will rest gently on and move smoothly over the cutting table. The rollers are yieldingly mounted on the base preferably as follows, see Figs. 2, 3 and 5. Spring bearing plates or strips p (see Fig. 3) of thin metal are arranged in pairs on the underside of the base A extending lengthwise thereof. These plates are oppositely disposed and each pair is centrally secured to the base A by a screw p^1 which passes through suitable semi-circular openings in each plate. The plates of

each pair are recessed at their inner sides near their ends, thereby forming openings p^2 for the rollers O, and are provided at their outer sides adjacent to the openings with 5 upturned bearing lugs p^3 which are connected by pins p^4 upon which the rollers are journaled. The plates p have suitable holes p^5 between their point of attachment to the base plate A, and the rollers, and posts p^6 10 depending from the base into said holes hold the plates from turning laterally on the attaching screw p' but do not interfere with the vertical cushioning movements of the bearing plates. Openings p^7 in the base 15 plate A over the rollers permit the rollers to yield or spring upwardly.

q represent elastic blocks or cushions which are confined in seats in the underside of the base plate A and depend therefrom into engagement with the free ends of the bearing plates p to prevent the latter from striking the base when flexed. The weight of the machine is carried by these cushions q and as the bearing plates p are capable of vertical movement, these plates are free to respond to the compression and expansion of these cushions. A yielding support or cushion is thus provided for the base of the machine which serves to greatly decrease any 20 jar caused by moving the machine over uneven surfaces, and prevents the vibrations of the machine when in motion from being communicated to the rollers. The screw p' serves at all times to hold the bearing plates 25 p in contact with the cushions q and in engagement with the guide posts p^6 . To remove the rollers from the base for cleaning and other purposes, it is only necessary to remove the attaching screws p' and detach 30 the bearing plates. The rollers and the bearing plates can then be readily cleaned.

To enable the operator to more clearly see the pattern on the cloth he is cutting, an incandescent lamp R is suspended from an 45 arm r pivotally secured to a bracket r' which extends forwardly from the frame C. The arm r is capable of swinging horizontally so that the lamp R may be located in front or at either side of the knife as may be desired. Instead of being secured directly and rigidly to its supporting arm, the lamp R is suspended therefrom by its conductor wires r^2 . These wires pass through an opening in the end of the arm r and are held suspended therein by a rubber ring or collar r^3 50 which embraces the lamp conductors and bears on the edges of the opening in the supporting arm. The ring r^3 tightly grips the conductors and can be moved up or down 55 thereon to secure the lamp at the proper height. Any other suitable means for supporting the conductor wires may be employed. A flexible support for the lamp is thus obtained and only a small part of the 60 vibrations of the machine are communi- 65

cated through this support to the lamp. A much steadier light is produced and the life of the lamp is greatly lengthened, as when a rigid support is employed, the rapid vibration of the lamp soon causes its filament to break and thus destroys its usefulness.

A guard wire S is suspended from the arm r and loosely embraces the base of the lamp to prevent undue oscillation thereof, and a metallic reflector s' partly surrounds the 70 bulb of the lamp to throw the light therefrom downwardly upon the pattern or cloth and also serves as a shield to prevent the bulb from being broken by coming into contact with any part of the machine.

I claim as my invention:

1. In a cloth cutting machine, the combination of a base, a standard mounted on said base, a motor supported by said standard and having its shaft arranged lengthwise of 85 the machine, a knife guided in said standard, a cross head secured to said knife and reciprocated by said motor, said cross head being substantially parallel with said shaft, and upright guide ways for said cross head arranged in front and in rear thereof in a vertical plane parallel with the vertical plane of said shaft and said cross head, substantially as set forth.

2. In a cloth cutting machine, the combination of a base, a standard mounted on said base, a motor supported by said standard and having its shaft arranged lengthwise of the machine, a knife guided in said standard, a cross head connecting said knife and 90 said motor shaft and arranged with its greatest width lengthwise of the machine and substantially parallel with said shaft, and upright guide ways for said cross head arranged in front and in rear thereof in a 100 vertical plane parallel with the plane of said shaft and said cross head, substantially as set forth.

3. In a cloth cutting machine, the combination of a base, a standard mounted on said 110 base, a motor supported by said standard and having its shaft arranged lengthwise of the machine, a knife guided in said standard, a cross head secured to said knife and reciprocated by said motor, said cross head 115 and said knife being arranged substantially parallel with each other and in the vertical plane of said standard, upright guide ways arranged in front and in rear of said cross head in the vertical plane of said standard, 120 and a support to which said guide-ways are secured arranged at one side of the vertical plane of said standard, substantially as set forth.

4. In a cloth cutting machine, the combination of a base, a standard mounted on said base, a motor supported by said standard and having its shaft arranged lengthwise of the machine, a knife guided in said standard, a cross head secured to said knife and recip- 125 130

rocated by said motor, said cross head and said knife being arranged substantially parallel with each other and in the vertical plane of said standard, upright guide-ways 5 arranged in front and in rear of said cross head in the vertical plane of said standard, and a support arranged at one side of the vertical plane of said standard, to one side of which support said guide-ways are secured, 10 and adjusting means for said guide-ways arranged on the opposite side of said support, substantially as set forth.

5. In a cloth cutting machine, the combination of a base, a standard mounted on said 15 base, a motor supported by said standard and having its shaft arranged lengthwise of the machine, a knife guided in said standard, a cross-head secured to said knife and reciprocated by said motor, and upright 20 guiding means for said cross-head arranged in front and in rear thereof and substantially to one side of the vertical plane of said knife whereby said guiding means do not obstruct the view of the knife on the opposite side of the machine, substantially as set forth.

6. In a cloth cutting machine, the combination of a base, a standard mounted on said base, a motor supported by said standard, 30 a knife guided by said standard, a cross head secured to said knife and reciprocated by said motor, a support, guide ways for said cross head at one side of said support and having lugs extending through holes in said 35 support, and an adjusting screw for said guide ways connecting said lugs at the opposite side of said support, substantially as set forth.

7. In a cloth cutting machine, a reciprocating cross-head for the knife, guide ways for the cross-head, an adjusting screw having a threaded engagement with one guide way, a nut mounted on the other guide way and having a threaded engagement with said 45 adjusting screw, and means for holding said nut from rotation and releasing it at will, substantially as set forth.

8. In a cloth cutting machine, the combination of a frame, a shaft journaled in said 50 frame and provided at one end with a crank, a knife, a pitman connecting said knife and said crank, a separate removable casing inclosing said crank and having a slot through which said pitman passes which slot is open 55 at one side for the passage of said pitman in removing said casing, and interlocking means between said casing and said frame

for detachably securing said casing thereto, substantially as set forth.

9. In a cloth cutting machine, the combination of a base, a spring-bearing plate, rollers journaled in the opposite ends of said bearing plate, elastic cushions between the ends of said bearing plate and said base adjacent to said rollers for holding said bearing plate out of contact with said base, and means centrally located between said rollers for holding said bearing plate in engagement with said cushions and detachably securing said bearing plate to said base, substantially as set forth.

10. In a cloth cutting machine, the combination of a base, a spring bearing plate, rollers journaled in the opposite ends of said bearing plate, a screw passing centrally through 75 said bearing plate for detachably securing it to said base whereby said bearing plate and said rollers may be removed from said base as a unit, guide studs secured to said base and engaging said bearing plate, and elastic 80 cushions between the ends of said bearing plate and said base, substantially as set forth.

11. In a cloth cutting machine, a base plate, a cloth-lifting plate, and a hinge connection for said plates comprising a hinge 85 lug on one plate provided with an open bottom slot, hinge lugs on said other plate connected by a hinge pin which is seated in said slot, and a headed screw secured to said slotted lug with its head engaging said hinge 90 pin to hold the same therein, substantially as set forth.

12. In a cloth cutting machine, the combination of a lamp, a support therefor on said machine, flexible conductors connecting 95 said lamp with the source of current in the machine and secured in said support to hold said lamp suspended therefrom, and a guard for said lamp secured in said support, substantially as set forth.

13. In a cloth cutting machine, the combination of a lamp, a support therefor pivotally secured to said machine, flexible conductors connecting said lamp with the source of current in the machine and secured in 105 said support to hold said lamp suspended therefrom, and a guard for said lamp secured in said support, substantially as set forth.

Witness my hand, this 29th day of August, 1907.

FREDERICK J. CLARK.
